UNITED STATES PATENT OFFICE

JENNIE M. BODENSIEK, OF NEW YORK, N. Y.

HOSE-SUPPORTER GRIPPING DEVICE

Application filed June 4, 1931. Serial No. 542,019.

This invention relates to corset hose-supporter gripping devices and to the means for maintaining same on the hose-supporter.

One object of the invention is to produce a device of the character described provided with a buckle or clasp for adjustably clasping same to a hose supporter or garter, without sewing the said garter to the clasp.

Another object of the invention is to provide a combined buckle and hose-supporter gripping device that will eliminate the use of double elastic for the hose supporter, thus allowing the buckle and gripping device to be moved as close to the corset as desired.

15 A further object of the invention is to produce a device of this character in which the usual button and gripping yoke is eliminated, thus giving to the device a neat appearance and eliminating any projection of the button and the discomfort of having the said button press into the flesh of the wearer when in sitting posture, and also preventing the stocking from being caught between the said button and its support, and the resulting run 20 in the said stocking.

A still further object of the invention is to provide a device of the character described having a wide hose gripper, so as to distribute the strain evenly on the stocking, thus 25 resulting in a better fit, with no wrinkles at the ankles or looped effect at the top.

Still another object of the invention is to produce a device of this character in which the hose may be firmly gripped without causing any twisting action to itself, or hose.

Another object is to produce a device of the character described in which the maximum simplicity of construction and operation is secured.

40 Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in 45 the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

55 The inventive idea involved is capable of receiving a variety of mechanical expressions, one of which, for the purpose of illustration, is shown in the accompanying drawings, in which—

Figure 1 is a perspective view of my improved gripping device and buckle.

Figure 2 is a front view in elevation thereof, shown as applied to a stocking.

Figure 3 is a sectional view at an enlarged scale, taken on line 3—3 Fig. 2, and

Figure 4 is a rear view of the device.

Referring now to the drawings in detail, 5 indicates the lower portion of a garment, preferably a corset, to which is secured an elastic strip of material 6, and a hose gripping device 7 is adjustably maintained on the said elastic strip.

The gripping device 7 comprises a base in the form of a loop member 8 made of non-corrosive wire having a pair of substantially vertical arms 9 connected by a lower horizontal bar 10 and terminating in a pair of arms 11 parallel to and spaced from the connecting bar 10. A second loop member 12 made of similar material as the loop member 8, is swingingly mounted on the first mentioned loop member 8 by means of a pair of ears 14 encircling the arms 11. Vertical arms 15 extend from the ears 14 and are bent inwardly into upper and lower oppositely disposed substantially U shaped portions 16 and 17 respectively, the lower portions 17 being connected to a horizontal bar 18 by means of rearwardly extending short arms 19. It will be noted that the horizontal cross bars 10 and 18 form means for clamping the edge 20 of a hose or stocking 21.

Pivotedly mounted on the arms 11 of the loop member 8 is a clasp or clamping lever 25 having a toothed or serrated portion 26 adapted to engage the elastic strip 6 against a cross bar 27 secured to the upper portion 100

of the loop member 8. A finger piece 28 at the lower end of the said clasp 25 permits of swinging same out of clamping engagement with the said strip 6. An ear 25a at 5 each end of the clasp forms the pivotal mounting means for the said clasp.

The operation of the device is as follows:—

To insert the stocking into the gripping device, the loop member 12 is swung outwardly in the direction of the arrow 30 Fig. 10 3 so as to bring the cross bars 10 and 18 out of engagement with each other and then bring the top portion 20 of the stocking 21 between the said bars after which the loop 15 member is snapped back into position shown in Fig. 3. The gripping device 7 is then bodily moved up or down on the strip 6, and clamped in position by manipulating the clamping lever or clasp 25.

20 It will be understood that due to the relation of the toothed portion 26 of the clamping lever 25 to the bar 27 and strip 6 any upward pull on the said strip will cause the said toothed portion to more firmly grip the strip against the bar 27. To loosen the clamping lever for the purpose of adjustment it is swung outwardly by lifting the finger piece 28, or by pulling downwardly 25 on the strip 6.

30 From the foregoing it will be seen that I have provided a combined clamp and buckle that will positively grip the hose without causing any runs therein and one that can be readily adjusted on the garter strip and avoid the use of a double elastic for the hose 35 supporter or garter.

It will also be seen that the combined gripping device and buckle may be slipped off the elastic strip 6 when the corset is laundered 40 without having to rip any stitches that usually secure the gripping device to the corset garter or elastic strip.

Having described my invention, what I 45 claim as new and desire to secure by Letters Patent is:—

1. A hose supporter gripping device, comprising a pair of loop members hingedly connected to each other, a bar on each of said members adapted to be brought into clamping engagement with each other, and a clamping lever pivotally mounted on one of the said members, for the purpose specified.

50 2. A hose supporter gripping device, comprising a pair of loop members hingedly connected to each other, a bar on each of said members adapted to be brought into clamping engagement with each other, a second bar on one of the said members parallel to the clamping bar and spaced therefrom, and a toothed clasp pivotally mounted on the last mentioned member in operative relation with the second mentioned bar.

55 3. A hose supporter gripping device, comprising a base, a pair of upper horizontal

arms forming a part of the base, a pair of substantially vertical arms bent from the said horizontal arms, a horizontal clamping bar connected to the vertical arms and parallel to and spaced from the horizontal arms, a second horizontal bar on the base near the said arms, a loop member pivotally mounted on the said arms, a horizontal bar at the bottom end of the said loop member adapted to be brought into clamping engagement with the base clamping bar, and a toothed clasp pivotally mounted on the upper arms in operative relation with the second mentioned horizontal bar.

4. A hose supporter gripping device adapted to be slidably supported on a strip of material, comprising a base member, pivot arms thereon, a clamping member pivotally mounted on the pivot arms, a toothed clasp pivotally mounted on the pivot arms, and a bar on said base member in operative relation to the toothed clasp, the said bar and clasp forming means for sliding the gripping device on the strip.
